CLAIM

The ornamental design for a container lid, as shown and described.

DESCRIPTION

FIG. 1 is a top perspective view of a first embodiment of a container lid showing my new design;

FIG. 2 is a top plan view thereof;
 FIG. 3 is a bottom plan view thereof;
 FIG. 4 is a front elevation view thereof;
 FIG. 5 is a rear elevation view thereof;
 FIG. 6 is a left side elevation view thereof;
 FIG. 7 is a right side elevation view thereof;
 FIG. 8 is a top perspective view of a second embodiment of a container lid showing my new design;
 FIG. 9 is a top plan view thereof;
 FIG. 10 is a bottom plan view thereof;
 FIG. 11 is a left side elevation view thereof, the right side view being the same;
 FIG. 12 is a top perspective view of a third embodiment of a container lid showing my new design;
 FIG. 13 is a top plan view thereof;
 FIG. 14 is a bottom plan view thereof;
 FIG. 15 is a front elevation view thereof, the rear view being the same;
 FIG. 16 is a left side elevation view thereof, the right side view being the same;
 FIG. 17 is a top perspective view of a fourth embodiment of a container lid showing my new design;
 FIG. 18 is a top plan view thereof;
 FIG. 19 is a bottom plan view thereof;
 FIG. 20 is a front elevation view thereof, the rear view being the same;
 FIG. 21 is a top perspective view of a fifth embodiment of a container lid showing my new design;
 FIG. 22 is a top plan view thereof;
 FIG. 23 is a bottom plan view thereof;
 FIG. 24 is a front elevation view thereof;
 FIG. 25 is a rear elevation view thereof;
 FIG. 26 is a left side elevation view thereof;
 FIG. 27 is a right side elevation view thereof;
 FIG. 28 is a top perspective view of a sixth embodiment of a container lid showing my new design;
 FIG. 29 is a top plan view thereof;
 FIG. 30 is a bottom plan view thereof;
 FIG. 31 is a front elevation view thereof;
 FIG. 32 is a rear elevation view thereof;
 FIG. 33 is a top perspective view of a seventh embodiment of a container lid showing my new design;
 FIG. 34 is a top plan view thereof;
 FIG. 35 is a bottom plan view thereof;
 FIG. 36 is a front elevation view thereof;
 FIG. 37 is a rear elevation view thereof;
 FIG. 38 is a left side elevation view thereof; and
 FIG. 39 is a right side elevation view thereof.

Front and rear views of the container lids have been omitted from the second embodiment, as they are identical to the front and rear views of the article as shown in FIGS. 4-5, respectively, of the first embodiment. Left and right side views of the container lid have been omitted from the fourth embodiment, as they are identical to the left and right side views of the container lid as shown in FIGS. 6-7, respectively, of the first embodiment. Left and right side views of the container lid have been omitted from the sixth embodiment, as they are identical to the left and right side views of the container lid as shown in FIGS. 26-27, respectively. The broken lines are shown for the purpose of illustrating parts of the article that form no part of the claim. The dot-dash lines represent the boundaries of the claim and form no part thereof.
